UNITED STATES PATENT OFFICE.

EUGENE S. BOUDINOT, OF WEBSTER CITY, IOWA.

DESIGN FOR A MATCH HOLDER.

Application filed July 14, 1924. Serial No. 10,141. Term of patent 3½ years.

To all whom it may concern:

Be it known that I, EUGENE S. BOUDINOT, a citizen of the United States, and a resident of Webster City, in the county of Hamilton and State of Iowa, have invented a certain new, original, and ornamental Design for a Match Holder, of which the following is a specification, reference being had to the accompanying drawing, forming part thereof.

The figure shows a perspective view of a match holder showing my new design.

I claim:

The ornamental design for a match holder, as shown.

Des Moines, Iowa, July 9, 1924.

EUGENE S. BOUDINOT.
